INVENTOR

BY Clarence R. Rader
ATTORNEY

UNITED STATES PATENT OFFICE.

RICHARD HOWELL, OF RIDLEY PARK, PENNSYLVANIA.

DESIGN FOR A FRUIT-JAR WRENCH.

SPECIFICATION forming part of Design No. 33,732, dated December 18, 1900.

Application filed August 7, 1900. Serial No. 26,198. Term of patent 7 years.

To all whom it may concern:

Be it known that I, RICHARD HOWELL, a citizen of the United States, residing at Ridley Park, Delaware county, Pennsylvania, 5 have invented a new and original Design for Fruit-Jar Wrenches; and I do hereby declare that the following is a full, clear, and exact description of the same.

Reference is to be had to the accompanying drawing, forming part of this specification, which represents a fruit-jar wrench embodying my new and original design.

As shown in the drawings, the leading or material feature of my design consists of the 15 transverse serrations A, extending around the inside of the approximately circular open

ring or body B of the wrench. The ends of the open ring or body B bend outward to form the diverging straight parts C, which have their extremities E curved inward, as shown. 20

Having thus described my design, I claim as new and desire to secure by Letters Patent of the United States—

The design for a fruit-jar wrench, substantially as herein shown and described. 25

In testimony whereof I have hereunto set my hand the 27th day of July, 1900.

RICHARD HOWELL.

In presence of—

JOHN A. KELLEY,
S. F. OGDEN.
